UNITED STATES PATENT OFFICE.

WILLIAM A. BRUNCKHORST, OF CHICAGO, ILLINOIS.

TILE ROOF AND ROOFING-TILE.

1,123,674.

Specification of Letters Patent.

Patented Jan. 5, 1915.

Application filed March 15, 1912, Serial No. 683,962. Renewed August 22, 1914. Serial No. 858,127.

To all whom it may concern:

Be it known that I, WILLIAM A. BRUNCKHORST, a citizen of the United States, residing at Chicago, in the county of Cook and State of Illinois, have invented new and useful Improvements in Tile Roofs and Roofing-Tiles, of which the following is a specification.

The object of my invention is to furnish a tile roof of exceptional strength, considering its weight; to facilitate manufacture and laying of the tile; and to secure closeness of joints, so as to prevent leakage.

In the drawings Figure 1. is a plan view of a roof formed of tiles embodying my improvements; Fig. 2. is a section on line 2—2 in Fig. 1; Fig. 3. is a section on line 3—3 in Fig. 1; Fig. 4. is a section on line 4—4 in Fig. 1; and Fig. 5. is a plan view of the under side of a main tile embodying my improvements.

Referring to the drawings, my roof is constructed mainly of tiles 6, consisting of a flat body ordinarily about twice as long as wide, which on its upper side is provided with ribs 7 adjacent to its longer edges, and which on its lower side, along its whole circumference, is provided with a heavy rib 8, a lip 9 projecting downward beyond rib 8 along one of the ends of tile 6; these features being modified however by the termination of ribs 7 a short distance from the ends of tile 6, and by the provision of a semicircular groove 10 in rib 8 at the middle of the end of tile 6 opposite the end at which lip 9 is located. In conjunction with tiles 6 I employ caps 11 which are of a length equal to that of tiles 6, are of semi-tubular section, save that their ends 12 are made solid for a length equal to the distance to which ribs 7 approach the ends of tiles 6, and which are of dimensions such as to be able to accommodate below them two ribs 7 of adjacent tiles 6 and to snugly fit into groove 10 of any tile 6.

In laying my roof I use preferably a sub-structure of steel with horizontal purlins. On the lowest pair of these purlins I place a row of tiles 6 side by side with lips 9 hooked over the upper purlin, and the other ends, containing grooves 10, resting

on the purlin below. I then place caps 11 over each pair of adjoining ribs 7, and thereupon place another row of tiles 6 with their lips 9 hooked over the next purlin 55 above and their lower ends resting on the lower row of tiles 6 and caps 11, disposing of tiles 6 in the upper row so that their grooves 10 will fit over caps 11 in the lower row, thus breaking joints; thereupon I 60 place caps 11 over ribs 7 in the upper row; and thus continue until my roof is completed.

While my tiles and caps are intended to be constructed chiefly of reinforced concrete—ribs 8 being particularly useful for the placing of reinforcements—I do not wish to confine myself to that material.

It is evident that instead of using ribs 7 and caps 11, I may adopt other means of 70 closing the vertical joints between tiles 6, such as pitch etc., omitting in such case grooves 10.

I claim:—

1. In tile roofs, the combination of suitable means of support, with main tiles 6 being flat on their upper surfaces, save as to two ribs 7 projecting along two opposite edges, and having on their lower sides a rib 8 along their whole circumference, with a lip 9 depending below such rib along one of the edges of such tile not provided with ribs 7, and a groove 10 formed in said rib 8 at the middle of the edge of each tile opposite the one provided with lip 9; and 85 semi-tubular auxiliary caps 11 fitting over adjoining ribs 7 and into grooves 10, and having solid ends 12.

2. As a new article of manufacture, a roofing tile 6 being flat on its upper surface 90 save as to two ribs 7 projecting along two opposite edges, and having on its lower side a rib 8 along its whole circumference, with a lip 9 depending below such rib along one of the edges not provided with ribs 7, and a 95 groove 10 formed in said rib 8 at the middle of the edge opposite the one provided with lip 9.

WILLIAM A. BRUNCKHORST.
